METHOD OF MAKING PRINTING ROLLS

John J. Ormond, Boston, Mass., assignor of two-thirds to Joseph D. Ramsey, Boston, Mass.

Application April 23, 1941, Serial No. 389,951

3 Claims. (Cl. 95—5.7)

This invention relates to methods of making printing members, and more especially to methods of making intaglio printing rolls of the type used in textile printing.

In making textile printing rolls, it is necessary to form intaglio printing portions of design subject matter repeated around the surface of a printing roll. Very careful preparation of the printing portions is necessary in order to prevent a break or line, along points where one of the designs joins a succeeding design, from appearing in a continuous web of cloth over which the roll is passed in carrying out the textile printing operation. This problem is made more difficult by reason of the fact that several different colors are usually desired to be utilized in juxtaposed relation to one another. The procedures now resorted to are slow, in some cases inaccurate, and require skilled labor, which greatly increases the cost of printed textiles.

A chief object of the present invention is to improve methods of making printing members and to devise a method of preparing a textile printing roll which includes procedures for forming continuous design printing portions around a roll surface without having any break or line occurring along those points at which the design portions are repeated. Another object of the invention is to provide a method of making a textile printing roll which may be quickly carried out, which requires less skilled labor, which is very accurate and which is adapted to effect substantial savings. Another object of the invention is to provide an improved photographic element particularly adapted to making textile printing rolls, and to present a method of making printing rolls by the use of photographic materials. Still another object of the invention is to devise improved methods of etching rolls.

Fig. 1 is a fragmentary plan view of a strip employed in carrying out the method of the invention;

Fig. 2 is a fragmentary elevational view illustrating application of the strip to a printing roll;

Fig. 3 is a fragmentary elevational view illustrating a printing roll finished in accordance with the method of the invention; and

Fig. 4 is a fragmentary elevational view illustrating a modified method of the invention.

The nature of the invention, and its objects, will be further understood from the following description and appended claims.

In textile printing, it is customary to provide copper printing rolls which have recessed printing surfaces, or intaglio printing portions, par-

ticularly adapted to holding large amounts of dyes or other materials applied on textiles. The roll is etched by some suitable acid such as iron perchloride, and etching is controlled to take place in selected areas on a roll surface by first applying acid resisting materials, such as asphaltum or other suitable substances. The acid resist outlines are customarily drawn in by hand or by the use of devices such as pantograph machines.

According to the invention, I form a series of design printing portions which are repeated around a roll surface along a helical path which extends from one end of the roll to its opposite end in a plane wrapped around the roll. This procedure of repeating design printing portions along a helical path on the surface of a roll may be carried out in several ways, and may make use of various instrumentalities.

20 In one method of the invention, a copper roll of suitable diameter and length is covered with a light-sensitive acid-resisting material as asphaltum. I then provide a strip of translucent material such as a translucent paper, and on the 25 paper I print with an opaque ink, such as lithographic printing ink, portions of subject matter or designs desired to be etched into the surface of the roll. The printed subject matter is arranged on the strip in an angular position with respect to its sides, so that it will occur on the 30 surface of the roll in a squarely disposed manner with respect to the ends of the roll after the strip is wound along a helical path around the roll with its edges in abutting relation. The strip 35 is of a length corresponding to the length of strip necessary to completely cover the surface of the roll when wound diagonally therearound, and each portion of the translucent strip carries that part of the design subject matter which it would 40 receive if the design were printed on the strip while wound around the roll.

The strip and roll are exposed to strong light such as photographic light, to expose uncovered parts of asphaltum. Thereafter the strip is removed and the ink material, together with the unexposed asphaltum, are washed away with a material such as turpentine, which cleanly removes the unexposed portions of the asphaltum in accordance with the design portions covered by the ink on the strip. The roll is then etched by placing it in a bath of acid as iron perchloride for a suitable length of time. If desired, various screens, ground lines and the like may be incorporated with the inked strip to provide ink-

retentive grounds of the type usually employed in textile printing rolls.

It is contemplated that the inked strip be formed in various ways. It may be cut with irregular edges which are particularly shaped to avoid breaking designs all the way around a roll. The subject matter may be divided up into squares on a master sheet and then applied on the strip so that a single design portion may occur within the width of the strip or may extend across several widths of the strip. The designs may be drawn on the strip or printed thereon either in a flat state or while wound around a roll of a similar diameter to the diameter of a roll to be etched. Various other methods of making the strip may also be resorted to as will appear more fully hereinafter.

Referring more in detail to the drawing, numeral 1 indicates a strip of translucent material such as translucent paper. A series of designs 2 is printed on the strip 1 as illustrated in Fig. 1, with the designs being arranged to occur angularly with respect to the parallel edges 3 of the strip.

Fig. 2 illustrates a textile roll 4 which is to be engraved. The outer periphery of the roll is covered with a coating 5 of a light-sensitive acid-resistant material such as asphaltum. Around this asphaltum surface is wound a strip 1 along a helical path, as illustrated in Fig. 2. By properly arranging the strip 1, a substantially vertical position of the designs 2 with reference to the axis of the roll 4 is achieved, while edges of the strip are brought into abutting relation throughout its position around the roll surface. The roll and strip assembly is exposed to light which hardens the asphaltum 5 at all points except those covered by the designs 2 on the strip, which are formed of an opaque ink. When sufficient hardening has been allowed to take place, the strip is removed and the unhardened areas of the asphaltum which occurred directly below the opaque ink designs 2 are dissolved away by the use of a suitable solvent of the conventional type, thus leaving bare the surface of the roll 4 at these points. The roll is thereafter immersed in a bath of etching reagent of some suitable character to form the etched designs 3 on the surface of the roll 4, which are adapted to receive ink and print in accordance with the conventional intaglio methods of roll printing.

Fig. 4 illustrates a modified type of strip 1 having irregular wavy edges 6, which are adapted to provide a means of going around designs to be continuously formed around the surface of the roll without having a break occurring in the designs. One method of utilizing a strip of irregular edge character is to apply a strip to a roll desired to be etched, and lightly mark out on the surface of the strip the desired designs which are to be printed thereon. With the designs thus roughly marked out, the edges of the strip can be cut along irregular paths which will avoid intersecting the designs. The strip may then be removed and inked with an opaque ink and utilized in the manner already described.

The method of the invention includes specific methods of etching which may be desired to be resorted to in carrying out the above noted process. One etching method consists in coating a roll surface with a light-sensitive coating material, such as a mixture of albumin, ammonium bichromate, and an acid-resistant ingredient. The coating is exposed and developed in the usual manner to provide exposed roll surfaces. The

roll is then subjected to a very short immersion in an acid bath, such as iron perchloride, to carry out a first "bite" which is relatively shallow in relation to the actual bite or depth which is desired to be obtained in the finished printing portions of the roll.

The first bite cuts very lightly into the roll surface. Immediately thereafter an acid-resistant material such as asphaltum, which is much more strongly acid-resistant than the albumin, is applied by means of the diagonally wound strip, for example, to those parts of the roll surface which are covered with the first acid-resistant material. None of the asphaltum is transferred to the roll surface which has been lightly etched. The result is to reinforce the first acid-resistant material in which the printing portions have been defined with a stronger acid-resistant material. Thereafter stronger bites with the acid may be carried out to obtain a proper depth of etch. This procedure combines the use of quick exposure and development from a coating of the albumin type, with the strongly acid-resistant character of a resist such as asphaltum.

Another etching procedure which may be desired to be resorted to, particularly in connection with metals of a harder character than copper, as for instance brass, steel and others, consists in coating a roll with light-sensitive asphaltum, and then printing an outline of subject matter desired to be etched, on the asphaltum coating, making use of a printing ink which is highly absorptive of metal powders. For example, an ink made up of linseed oil and a pigment such as red lead is suitable and will readily absorb relatively large amounts of metallic powders such as aluminum or bronze. A tacky ink image of this character is sprinkled over with a powder such as aluminum or bronze. The powder is absorbed in the ink-covered areas, but may be readily blown away from the relatively slick surface of the dry asphaltum coating at all other points.

The metallic powder renders the ink image highly opaque and the asphaltum coating may then be exposed to strong light to harden all portions of the asphaltum not covered by the opaque ink. The opaque ink and unhardened portions of the asphaltum may then be dissolved away by the use of a suitable solvent such as turpentine, which exposes the metal surface of the roll in accordance with subject matter desired to be etched thereon. The roll is then immersed in a bath of a strong acid such as nitric or muriatic acid, to obtain desired etching.

The coating of asphaltum first applied on the roll is of sufficient strength to resist penetration by these strong acids. However, the procedure outlined allows this relatively strong acid-resistant asphaltum to be removed along sharply defined lines in accordance with a design desired to be reproduced, and this result is obtained quickly and efficiently.

The procedure of forming repeated design printing portions along a helical path which passes through a plane wrapped around a cylinder may be repeated with respect to other rolls which are to carry additional colors making up a multicolor design. It is pointed out that the use of an inked strip of translucent material, diagonally wound around a roll to be etched, illustrates one method of forming repeated design printing portions, various other ways of using a diagonally wound strip may be resorted to. For example, a strip of flexible material, which need

not necessarily be translucent, is inked with desired design portions, utilizing an ink of a character which is opaque or can be rendered so by some procedure such as one of those already noted. The strip is wound around a roll surface coated with light-sensitive asphaltum as described, and thereafter the strip is removed. The ink is offset to the asphaltum and treated to render it opaque. The coating is exposed to light and developed. Thereafter etching is carried out to obtain the desired printing portions.

In printing subject matter on the strip by mechanical means, various kinds of printing plates may be resorted to, as lithographic printing members, relief printing members, and intaglio printing members. It is also intended that the formation of printing portions, along a helical path, on a roll surface to avoid lines of other indications of lapping or breaking on the roll surface, may be carried out with respect to other kinds of printing rolls than the intaglio printing rolls used for textile printing, with which this invention is particularly concerned. For example, relief printing rolls such as embossing rolls, lithographic printing rolls and other types of rolls, may be desired to be prepared by the method of the invention.

While I have shown a preferred embodiment of the invention, it should be understood that various changes and modifications may be resorted to, in keeping with the spirit of the invention as defined by the appended claims.

I claim:

1. That improvement in methods of etching printing rolls which comprises providing a light-sensitive coating on a printing roll, then transferring opaque designs to the surface of the light-

sensitive coating by means of a diagonally wound strip on which the opaque material is first applied, said opaque material occurring angularly with respect to the parallel edge of the strip
5 whereby the design, when applied on a light-sensitive coating, occurs squarely with respect to the axis of the printing roll, exposing the roll to light to harden parts of the light-sensitive coating on the printing roll, removing unhardened parts of the light-sensitive coating, and etching.

2. That improvement in etching printing rolls which comprises providing a light-sensitive coating on a printing roll, preparing a translucent strip of material with designs of opaque material,
15 said designs occurring obliquely with respect to edges of the strip and in spaced relation thereto, arranging the strip in a diagonally wound manner about the light-sensitive coating so that the vertical axis of each of the designs occurs perpendicularly with respect to the axis of the roll, exposing to light to harden portions of the light-sensitive coating, removing unhardened portions of the light-sensitive coating, and etching.

3. That improvement in methods of making printing rolls which comprises providing a light-sensitive coating on a printing roll, arranging a diagonally wound strip about the surface of the light-sensitive coating, said strip being of a translucent character and including a series of opaque
30 designs angularly arranged in spaced relation between the edges of the strip, said edges of the strip being of irregular formation, exposing to light to harden portions of the light-sensitive coating, removing unexposed portions of the coating, and etching.

JOHN J. ORMOND.
